UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

PAPER AND LIKE MATERIAL CONTAINER.

Application filed April 26, 1924. Serial No. 709,246.

To all whom it may concern:

Be it known that I, WILBUR L. WRIGHT, a citizen of the United States of America, and resident of Fulton, county of Oswego,

5 State of New York, have invented certain new and useful Improvements in and Relating to Paper and like Material Containers, of which the following is a specification.

This paper container invention relates particularly to the end closures for containers and for container covers, composed of fibrous sheet material, such as more or less flexible paper, pulp board, mill board or the like; and the objects and nature of the invention 10 will be readily understood by those skilled in the art in the light of the following explanations of the accompanying drawings that illustrate the preferred mechanical expressions or embodiments of my invention 15 from among other forms, constructions and arrangements within the spirit and scope thereof.

Heretofore, it has been to all intents and purposes, impossible to produce a satisfactory really liquid tight paper container having a so-called single bottom, i. e. where the end closure is composed of a single flanged paper disk secured in the end of the barrel by crimping the end of the barrel with, or 20 to enclose, the flange of the disk. I have discovered that the tendency of such single bottom paper containers to leak, is due to the distortion of the disk flange by the crimping process and the formation therein 25 of slight creases, wrinkles, or surface fissures, that form leads for the liquid from the container through which the liquid by capillary action, seepage, or otherwise, is caused to penetrate the crimp and work out around 30 the extreme edge of the body wall and onto the outer surfaces of the disk and crimp. The crimping process in securing such single bottoms, always tends to open up a gap or 35 space between the inner surface of the container barrel and the outer surface of the annular angular edge portion of the disk, where the flange depends into the crimp, and 40 this annular gap opening into the container leads directly down into the crimp between the outer surface of the disk flange and the 45 inner surface of the barrel and increases the tendency to leakage and seepage along or by means of such wrinkles and creases within 50 the crimp.

55 It is an object of my invention to provide

a simple, effective and economical paper material (or the like) end closure for paper material (or the like) barrels, that will overcome the hereinbefore mentioned difficulty, and that will reduce to the minimum possibility of liquid leakage. 60

With this and other objects in view, my invention consists in certain novel features in construction, and in combinations and arrangements as more fully and particularly 65 pointed out and specified hereinafter.

Referring to the accompanying drawings, forming a part hereof:—

Fig. 1 is a longitudinal sectional view showing part of a cylindrical paper container having an end closure embodying my 70 invention.

Fig. 2 shows in longitudinal section, part of a paper container, longitudinally tapered for nesting, having a bottom closure in accordance with my invention. 75

Figs. 3, 4, and 5, are sectional views of paper containers having end closures in accordance with my invention secured by crimps of different formations. 80

Figs. 6 and 7 are longitudinal sections showing various steps in the method of providing cylindrical containers with the end closure of my invention.

Fig. 8, is a longitudinal section of a tapered paper container having flanged disks therein preparatory to completing the end closure of my invention. 85

The cylindrical paper container, partially illustrated, consists of a body or barrel 1, 90 constructed in any suitable manner of sheet paper, such as suitable pulp board or other flexible sheet or fibrous material or the like, and closed at one end by closure consisting of a main or major sheet paper material 95 disk 2 having annular flange or skirt 2^a, and a superimposed cooperating inner packing or sealing sheet paper material disk 3 having relatively short plain or smooth flange 3^a, the two disks being locked and secured to and within the barrel, to complete the closure, by any suitable crimp, whereby the lower end of the barrel encloses the flange of the major disk and forms the depending annular rim 4. 100

105 Various formations can be utilized or means provided for thus locking or securing disks to and within the barrel 1. In the formation of Figs. 1 and 2, the projecting end 1^a (Figs. 7 and 8) of the barrel extend-

ing beyond the flange 2^a, is contracted and turned inwardly across the end edge of flange 2^a and is then turned toward the outer surface of disk 2 and pressed radially outwardly with end extremity 4^a, turned outwardly and tucked into the crimp, forming a lock, and during this crimping operation great pressure is applied to tighten the crimp and compress the same longitudinally 10 toward the flat bodies of the disks.

In the formation of Fig. 3, the disks are secured by crimping the barrel end and flange 2^a, and the crimp 4^b, is locked by forcing into an annular groove 2^b in the major disk 2.

In Fig. 4, there is shown another form of securing crimp 4^c, wherein the barrel end and flange 2^a, are rolled and compressed together.

Fig. 5, shows another form of crimp 4^d and lock.

Heretofore, the major disk 2 and its flange, and various forms of securing crimps, for instance approximately such as 26 more or less diagrammatically illustrated among others, have been used to form single bottom containers, and leakage has resulted, as hereinbefore explained because of the annular gap necessarily opened between the 30 inner usually smooth surface of the barrel and the annular outer surface of the disk near the base of the flange, said gap leading into the portion of the crimp where the paper is necessarily distorted and wrinkled 35 by the crimping process.

I have discovered that this leakage can be prevented and a liquid tight paper container produced, without prohibitive added expense or material change in the paper container production method, by the provision 40 of the inner, sealing or packing disk 3, having the short usually smooth flange 3^a, with the inner disk facing the inner surface of the major disk 2 and with the short flange 45 3^a tightly held and compressed between the flange of the major disk and the inner surface of the barrel 1 and closing, packing or sealing the hereinbefore mentioned gap, but terminating short of the actual crimp, i. e. 50 the short flange 3^a, preferably terminates short of or above the wrinkled distorted portion of flange 2^a that is within or actually forms a part of the crimp. In other words, in the completed container the major disk 2 is closely fitted or nested within the sealing disk 3, with the short comparatively smooth flange 3^a, exteriorly fitting down around the comparatively smooth exterior surface of the upper or base portion of the 55 flange 2^a.

The inner or sealing disk 3 is usually composed of comparatively thin sheet paper material and is usually water proofed. The major disk 2 is preferably composed of 60 thicker sheet paper material, usually of a

cheaper grade of pulp board than the inner disk which thin inner disk can be composed of a good grade of paper, for instance a good manila sulphite. However, I do not wish to so limit my invention. The inner 70 disk 3 is tightly and permanently secured as a part of the closure, by its short flange which is gripped and compressed between the barrel and major disk, rendering the annular joint at this location liquid tight, 75 and furthermore the sealing disk is by its short flange thus permanently held to place and cannot be accidentally displaced, as sometimes happens with the inner non-flanged disks of a certain double bottom 80 container now extensively made and sold.

Any moisture that may work into and penetrate the short flange of the inner or sealing disk of my present invention will cause said flange to tend to swell and thus 85 the more tightly close the joint against liquid leakage, although if so desired, paraffine or other waterproofing material can be employed to aid in cementing the inner disk in position and sealing against leakage. 90 The sealing disk 3 having a short flange 3^a, is easy to draw by dies to disk form with a very smooth-surfaced flange, a smooth flange that can be tightly compressed between the smooth surface of the barrel and the smooth surface upper or base portion of flange 2^a, of the major disk, without the formation of creases or other leads for downward liquid seepage. As the flange 3^a is short, it is not 95 distorted by the crimping process as to 100 produce creases and the like that tend to leakage.

In the process of bottoming paper containers, according to any present invention, the open end cylindrical paper body or barrel 1 is placed over a mandrel, with the upper end of the barrel projecting the proper distance upwardly above the upper end or top working face of the mandrel. By the utilization of any suitable mechanism, the 105 flanged disks 2, 3, are produced, preferably in flaring or dish form (see Fig. 6) and nested with the major disk 2 within and over the sealing disk 3. The two nested disks as a unit are forced down into the projecting upper end of the barrel, by a suitable reciprocating plunger, or in any other suitable way, until seated on the upper end of the mandrel. The flanges of the two disks are thus brought to cylindrical form within 110 the body (Fig. 7) and are tightly wedged and approximately compressed or held under pressure within the body. The mandrel with the body and disks as in Fig. 7, are then brought into operative relation to a 115 suitable crimping or spinning head, that completes the bottom closure by the formation of any suitable crimp, such as any one of the forms disclosed by the drawings, or 120 any other suitable for the purpose. In fact 125 130

I do not wish to limit my invention to any particular crimp formation or other means for securing the disks and barrel together.

- Where the paper bodies are of truncated cone formation, or longitudinally tapered, for nesting the containers for packing, (Figs. 2, 8) the permanent bottoms are usually applied to the smaller diameter ends of the bodies.
- 10 In bottoming such tapered barrels, the nested disks are first properly located on the upper end of a mandrel, and the tapered paper body is then forced down on the mandrel, large open end first, and over the nested disks, until the disks are brought to form and the body reaches the longitudinal position, with respect to the disks, about as shown by Fig. 8. The barrel and disks are then ready for the crimping operation, 20 which will produce the formation of Fig. 2, or any other suitable securing crimp or other means. By the use of the term "paper material" in the claims, I mean, the material hereinbefore referred to and the equivalent 25 thereof.

It is evident that various departures might be resorted to without departing from the spirit and scope of my invention and hence I do not wish to limit myself to the exact 30 disclosures hereof.

What I claim is:

1. A thin sheet paper material barrel having a liquid tight permanent inset end closure embodying a flanged imperforate major disk and a correspondingly flanged inner disk enclosing at least the inner end of the major disk and an annular longitudinally and radially compressed locked crimp securing both disks to and in the barrel, said end 35 closure consisting essentially of said major disk drawn from sheet material, and said inner disk drawn from thin flexible sheet paper material tightly fitting and facing the inner surface of the major disk and having 40 its annular flange throughout its length concealed and compressed between the major disk flange and surrounding inner surface of the barrel and thereby holding the inner disk as a permanent part of the end closure 45

and sealing the annular joint between the 50 inner surface of the barrel and the major disk against liquid seepage along the major disk flange to the lock crimp.

2. A thin sheet paper material barrel having a permanent liquid tight double disk end 55 closure consisting essentially of a major disk having an annular flange, said disk drawn from sheet material, and a thin flexible sheet paper material inner disk having a short annular flange, said inner disk being drawn 60 tightly over the major disk with its flange concentric with the major disk flange and tightly gripped between the major disk flange and the inner surface of the barrel to seal the joint between the inner surface 65 of the barrel and the major disk against liquid seepage and to secure the inner disk as a permanent part of the end closure, said major disk flange and the barrel end being rolled and longitudinally and radially compressed to form a permanent locked crimp. 70

3. In the method of forming a permanent liquid tight end closure for a paper container barrel, those steps which consist in drawing a major closure disk with an annular 75 flange from sheet material, drawing an inner disk with an annular flange from thin flexible sheet paper, nesting said two disks with the inner disk enclosing at least the end portion of the major disk, then forcibly driving 80 said two nested disks longitudinally into the container barrel to tightly draw the inner disk over the inner face of the major disk and to tightly compress the inner disk flange between the inner surface of the barrel and 85 the major disk and thereby seal the annular joint between the major disk and surface of the barrel against liquid seepage and to secure the inner disk as a permanent part of the end closure, and then permanently securing the disk and barrel together by a 90 rolled locked crimp under longitudinal and radial pressure.

In testimony whereof I have hereunto set my hand at Fulton, N. Y., this 24th day of 95 April, 1924.

WILBUR L. WRIGHT.
